UNITED STATES PATENT OFFICE.

AUGUSTINE SHELBYNE, OF SOUTH PASADENA, CALIFORNIA.

AIR-BRUSH NOZZLE.

Application filed October 16, 1925. Serial No. 62,775.

My invention is an air brush nozzle of the type for projecting paint or like material by means of compressed air and having rotatable fluid and air nozzles adapted to give 5 a straight or a spread jet of fluid and to move together in changing the plane of the spread jet.

The particular feature of my invention is in the nozzle combining the inner fluid and 10 the outer air nozzle, both mounted for rotary motion, the air nozzle having a partial rotation on the fluid nozzle.

My invention may be utilized with the 15 controlling mechanism of my prior applications.

An object of my invention is to form an air brush nozzle with both the central fluid nozzle and the outer air jet nozzle which gives the cross spray, mounted to be 20 rotatable to eliminate wear and loosening of the air nozzle relative to the fluid nozzle. By this means, in changing the plane of the spread of the jet both nozzles are rotated in the desired direction. The air nozzle also 25 has a slight relative movement on the inner fluid nozzle to allow quick changing from straight to spread jets.

I preferably utilize a pistol type air brush having a bore in the outer end and with the 30 fluid duct entering at the base of the bore and the compressed air near the outer end. A fluid nozzle with a cylindrical inner portion is mounted in the bore and has washers to form a fluid tight seal with seats in the 35 bore. This nozzle preferably has an annular face on which is positioned the air nozzle. This latter is held in proper position by a tightening collar which functions to force the washers on the fluid nozzle 40 tightly against their seats, thus making an air and fluid seal. Cooperative ducts lead from the air bore into the air nozzle whereby the fluid may have a spread jet. Rotation of the air nozzle with the fluid nozzle 45 shifts the plane of the jet and the air nozzle has a limiting movement operated by the hand to quickly shift the jet from the straight to the spread as desired.

My invention will be more readily understood from the following drawings, in 50 which:

Figure 1 is a longitudinal section of a pistol type of air brush, illustrating my

nozzle of this application on the discharge end thereof.

Fig. 2 is a horizontal section of Fig. 1 55 on the line 2-2 taken in the direction of the arrows.

Fig. 3 is a vertical transverse section of Fig. 1, on the line 3-3 in the direction of 60 the arrows.

Fig. 4 is a positive view of the air jet nozzle piece.

Fig. 5 is a partial transverse section on the line 5-5 of Fig. 1 in the direction of 65 the arrows, showing the lateral air jets of the stationary and turning nozzle elements in register to give a spreading jet.

Fig. 6 is a section similar to Fig. 5, showing the outer air jet nozzle partially rotated and out of register, thus giving a 70 straight jet of paint.

Fig. 7 is a diagrammatic view showing the nozzle positioned to give a spread of the jet in a horizontal plane.

Fig. 8 is a similar view, illustrating the spread in a vertical plane by the rotation of the fluid nozzle and the air nozzle co-operating therewith.

Referring particularly to Fig. 1, the pistol type of air brush has a pistol grip handle 1 with an air duct 2 therethrough and a stock 3 with a longitudinal air passage 4, a valve 4' controlling the flow of air leading into a bore 5 forming an air chamber at 85 the outer end of the stock. A spigot 6 projects downwardly from the stock and forms the inlet for paint or the material being sprayed, this ending at the back of the bore. The flow of paint is controlled by a tapered 90 valve plug 7 having a stem 8 operated by the trigger 9 as will be hereafter described.

A paint cylinder 10 is mounted in the bore 5 and is preferably constructed with an inner flange 11, an outer flange 12, the latter 95 having a shoulder 13 around which a gasket 14 may be placed. This gasket is designed to engage an abutting surface 15 of the stock and a second gasket or washer 16 placed on the outside of the paint cylinder 100 is adapted to engage the abutment 17 formed in the stock. The cylinder 10 is slightly smaller at its portion 18 than the inner end of the bore 19 to allow free sliding motion to the cylinder.

The outer end of the paint cylinder is

- provided with an integrally formed air jet annulus 20, having an aperture 21 there-through adjacent the outside periphery of the paint cylinder and a pair of apertures 22 positioned near the outer edge of the said annulus. These apertures form passages for the air controlling the jet as hereafter described. The air cylinder has a tapered outer end 23 with a short cylindrical portion 24 forming the nozzle for the paint, this nozzle being controlled by the tapered valve plug 7; the stem of the plug being provided with spider arms 25 sliding on the interior surface of the paint cylinder and forming an accurate guide. A stuffing box 26 is formed in the stock to accommodate the sliding movement of the valve stem 8; the latter being adjustably connected to the trigger by the adjusting nut 27 and a yoke 28, the trigger being swivelly mounted on the swivel pin 29 in the stock and swivelly connected to the yoke 28 by a pin 30. A plunger 31 pressed by the spring 32 operates against the movement of the trigger.
- 25 The outer end of the stock has screw threads 33 on which are threaded a collar 34, the latter having a cylindrical outer section 35 with an inwardly turned neck 36. The air nozzle 37 constructed with the rim 38 is machined on the outer surface 39, the inner surface 40 and the edge 41. The base 42 is also machined. This is to give an accurate fit with the collar 34 and against the outer surface 43 of the annulus 20; this annulus 35 having a slight clearance 44 between its outer periphery and the cylinder of the bore forming the air chamber 5. The inner surface 20 of the rim forms a close fit with the periphery of the annulus 20 but not sufficiently 40 tight to prevent the relative rotation, nor is the fit of the outer surface 39 sufficient to prevent the relative rotation of the sleeve 34 and the air nozzle 37.
- 45 The air nozzle has a tapered inner surface 45 spaced from the tapered surface 46 of the paint cylinder 10 forming a space 47 through which air is discharged through the aperture 21 in the annulus 20. A pair of ducts 48 having lateral outlets 49 are constructed in 50 the prongs 50 of the air nozzle and provide for the lateral air jets.
- 55 The air nozzle 37 has projecting from its base 42 a pin 51, the latter fitting in a slot 52 of the annulus 20 of the paint cylinder. This allows a limited relative movement of the air nozzle and the paint cylinder.
- 60 The manner of assembling and utilizing my air brush nozzle is substantially as follows:
- 65 When the collar 34 is screwed tightly on the threads 33 the neck 36 draws the air nozzle inwardly and as the base of this latter presses on the annular outer end of the air cylinder 10 this element is thrust inwardly until the gaskets or washers 14 and 16 form

a liquid tight joint between the flanges 11 and 12 of the paint cylinder and the abutment surfaces 15 and 17 of the bore 5 in the stock of the pistol air brush. It will be noted that the various elements are designed 70 so that there is always a space 53 between the inner edge 54 of the rim 38 of the air nozzle and the outer end 55 of the end of the stock.

When it is desired to use a straight jet of 75 paint the air nozzle 37 will be adjusted so that the apertures 22 in the annulus 20 and the ducts 48 in the air nozzle are out of register; the discharge of air being through the aperture 21 and the space 47 discharging an 80 annular jet of air around the central jet of paint.

When it is desired to give a spray or spread to the paint, the nozzle 37 is slightly rotated until the apertures 22 and the ducts 85 48 are in register, thus allowing a flow of air in a cross direction on the central jet. The pin 51 and the slot 52 give a limited movement and as this is only of slight extent the spray may be readily and quickly changed 90 from the straight to the spread by the slight rotation of the air jet nozzle. This may be manipulated by hand or by means of a wrench should it for any reason stick. It will be understood that the flow of paint is 95 controlled by the trigger 9 and the flow of air being adjusted by means of the valve 4.

Figs. 7 and 8 indicate diagrammatically how the plane of the spread of the jet may be readily altered by rotating the air nozzle and the fluid nozzle therewith. Presuming the air brush is operating with a straight jet with the apertures 22 and the ducts 48 out of register, then when the air nozzle is rotated until these are brought into register, 100 a spread jet will be given and in this position the pin 51 will be at one end of the slot 2. The plane of the spread jet may then be changed by further rotating the air nozzle in the same direction. It is preferable to have the relative positions of the pin 51 and the slot 52 in regard to the cooperative apertures 22 and the ducts 48 such that rotating the air nozzle tends to tighten the sleeve 34 instead of tending to unscrew the sleeve. While there is a certain resistance of the packing washers 14 and 16 against the respective seats, this may be overcome sufficiently to allow rotation of both the fluid nozzle and the air nozzle together and still make a substantially air and fluid tight joint.

Although the type of adjustable air nozzle that I have disclosed is simple in design, nevertheless it may be modified in general features or in detail to suit specific types or makes of air brushes so that a quick and simple change can be made from a straight to a spread jet of different characters. Such changes may be incorporated in my inven- 125 130

tion without departing from the spirit thereof as set forth in the description, drawings and claims.

Having described my invention, what I claim is:

1. An air brush nozzle comprising in combination a rotatable nozzle having a central fluid jet, a rotatable air jet nozzle mounted on the face of the fluid jet, means to hold the air nozzle against said face to permit rotation thereof and an air passage through the face of the fluid nozzle having continuous register with an air passage to the central jet and air passages through the face of the fluid jet having registering and unregistering connection with the air nozzle jets on rotation of said air nozzle in opposite directions.
2. An air brush nozzle comprising in combination an air brush having a fluid jet with a disc-like face, an air jet nozzle rotatably mounted bearing against said face and passages through the disc-like face leading to the fluid nozzle and to the air jet nozzles, said air jet nozzles being movable out of register by partial rotation of the air nozzle to give a straight or a spreading discharge of the fluid.
3. An air brush nozzle comprising in combination an air brush structure having a stock portion, a passage for fluid, a bore at the end of the stock and a passage for air to said bore, a fluid nozzle mounted in the bore having a straight jet, a partially rotatable air jet nozzle mounted on the face of the fluid nozzle, and forming a central nozzle, a passage for air through the face of the fluid nozzle to the central nozzle, passages through the face of the fluid nozzle adapted to register with ducts through the air nozzle, and means to adjustably secure the air nozzle to the stock of the air brush, said air nozzle bearing against the face of the fluid nozzle.
4. An air brush nozzle as claimed in claim 3, in which the means to adjustably connect the air nozzle to the stock comprises a sleeve screw threaded on the end of the stock engaging the air nozzle and permitting rotary movement of the air nozzle relative to the stock.

5. An air brush nozzle comprising in combination an air brush having a stock with a bore therein, a fluid nozzle inserted in said bore, said fluid nozzle having an annular outer flange closing the end of the bore, a fluid passage through the stock to the fluid nozzle, an air passage through the stock to said bore, an air jet nozzle rotatably mounted on the annular flange of the fluid nozzle and having lateral air ducts therethrough, an air aperture through the annular flange, the air nozzle and the fluid nozzle being spaced to form an air passage from the said aperture to the fluid jet, a plurality of aper-

tures through the annular flange adapted to register with the air ducts in the air nozzle and a collar threaded on the stock engaging the air nozzle to allow rotary movement thereof, said rotary movement shifting the apertures through the annular flange and the ducts in the air nozzle in and out of register.

6. An air brush nozzle as claimed in claim 5 having in addition a flange on the fluid nozzle, a compressible gasket thereon bearing thereagainst, an abutment on the stock and said air nozzle bearing against the annular flange to compress the gasket on the tightening of the sleeve.

7. An air brush nozzle as claimed in claim 5, in which the annular flange of the fluid nozzle has an arcuate slot and the air jet nozzle is provided with a pin engaging said slot to allow limited rotary movement to the air jet nozzle.

8. An air brush comprising in combination a stock having a bore in the end thereof, an air passage leading to said bore and a fluid passage leading to the base of the said bore, a fluid cylinder having a flange, a compressible gasket bearing against said flange, an abutment seat formed in the base of the bore to support said gasket, the fluid cylinder having a tapered nozzle and an annular outer flange adjacent said nozzle, an air jet nozzle bearing against the annular outer flange, said nozzle having a plurality of air ducts therethrough and being spaced from the tapered fluid nozzle, the said outer flange having an aperture therethrough adapted to continuously register with the space between the air nozzle and the fluid nozzle and having a plurality of apertures adapted to register with the air ducts in the air nozzle and a collar threaded on the stock, said collar engaging the air nozzle to allow rotation thereof and whereby the collar causes the compression of the gasket through the air nozzle bearing against the outer flange of the fluid cylinder.

9. An air brush body having an air chamber in the outer end thereof, a fluid nozzle passing through said air chamber, an air jet nozzle rotatably mounted on the face of the fluid jet and having a plurality of air ducts therethrough, the face of the fluid nozzle having apertures to register with the said ducts and an aperture positioned between the air jet nozzle and the fluid nozzle, a collar threaded on the end of the air brush engaging the air nozzle to allow said air nozzle to have slight rotary movement and means operatively connecting the fluid nozzle and the brush body to form a fluid and air-tight connection by the threading of the collar on the air brush body, said collar forcing the air nozzle against part of the fluid nozzle.

10. An air brush nozzle comprising in combination a fluid nozzle rotatably mounted in an air brush, an air nozzle bearing on the fluid nozzle and rotatable thereon, said nozzles being interconnected to be rotatable in unison. 35
11. An air brush nozzle as claimed in claim 10 in which the interconnecting means allows limited relative rotary movement to 10 change the jet from a straight to a spread type of jet. 40
12. An air brush nozzle as claimed in claim 10 having clamping means securing the air nozzle to the air brush and said air 15 nozzle bearing on the fluid nozzle to hold same in adjusted position. 45
13. An air brush nozzle comprising in combination an air brush stock having a bore in one end, fluid and air passages leading into different portions of the bore, an 20 inner fluid nozzle rotatably mounted in the bore and having a front bearing surface, an air nozzle rotatably mounted on the said bearing surface, clamping means to hold 25 the air nozzle on the said face in proper relation to the bore and packing means associated with the fluid nozzle and the bore to form an air and fluid seal on operation of the clamping means. 50
14. An air brush nozzle as claimed in claim 13, in which the air and the fluid 30 55
15. An air brush nozzle comprising in combination a fluid nozzle rotatably mounted in an air brush, an air nozzle mounted on the fluid nozzle to have partial rotation thereon, air jets cooperative to give a straight jet in one position of the air nozzle relative to the fluid nozzle and a spread jet in another position and the combined rotation of the fluid and air nozzles changing the plane of the spread jet. 60
16. An air brush nozzle comprising in combination an air brush stock having a bore in one end, air and fluid passages leading to said bore at substantially opposite ends thereof, a fluid nozzle rotatably mounted in the bore, an air nozzle bearing against part of the fluid nozzle and mounted for partial rotation thereon, packing means operative between the fluid nozzle and the bore to form an air and fluid-tight seal, means connecting the air nozzle to the air brush stock, said means forcing a tightening of the packing and cooperative air passages from the bore to the air nozzle. 65

In testimony whereof I have signed my name to this specification. 70

A. SHELBURNE.
